METHOD OF SPINNING AND WINDING
ARTIFICIAL SILK FILAMENTSHendrik Gerardus van der Waals, Arnhem,
Netherlands, assignor to American Enka
Corporation, a corporation of DelawareApplication November 24, 1933, Serial No. 699,631
In Germany October 13, 1933

3 Claims. (Cl. 18—54)

The present invention concerns a new method of spinning and winding artificial silk filaments.

More especially the invention has to do with a new and novel method for decreasing the difference in the dyeing affinity of artificial silk threads between the exterior and interior portions of spun packages, such as threads wound on spinning spools or in cake form.

One object of the present invention is to provide a method which will give the threads running from the spinning nozzle to the collecting device, such as spool or spinning centrifuge, a certain amount of stretch, and change the intensity of stretch from the beginning to the end of the winding process.

Another object of the present invention is a method for giving the freshly spun thread on its way between the spinning nozzle and the collecting device a predetermined stretch, increasing the amount of stretch from the beginning to the end of the winding process and providing means for reducing the winding tension of the thread. In the production of artificial silk, especially according to the wet spinning process, viscose- or copper-process and the like it is known that the thread packages obtained, particularly bobbin packages, but also cakes produced in the so-called spinning centrifuges, show variously strong affinity to dyestuffs on the exterior and interior portions of the same, and to wit the affinity to dyestuffs is stronger at the exterior portions of the bobbin packages and at the interior portions of the centrifugal packages. In order to compensate these various affinities to dyestuffs quite a number of suggestions have been made, which, however, have not brought complete success.

According to the present invention it has been made possible to solve this problem in a very effective manner with new means. According to this a special positively driven godet or drawing-off roller is interposed in front of the real winding member. This draws off the thread as much as possible without slip and delivers it to the winding member running at a certain, e. g., constant winding speed. The important thing in the invention is that the drawing-off speed of the interposed godet is controlled during the winding process in such a manner that the artificial thread is increasingly more and more stretched between the interposed godet and the real, positively driven winding member. In this way it is accomplished that the exterior portions of the spinning bobbin packages are wound with threads with greater stretch than otherwise, and the interior portions of the spinning cake are also

formed with threads with greater stretch. As threads with greater stretch have a less affinity to dyestuffs, the undesirable greater affinity to dyestuffs of the exterior portions of the bobbin package and the interior portions of the cake is diminished and made to correspond with the smaller affinity to dyestuffs in regard to the interior portions of the bobbin packages and of the exterior portion of the spinning cake. It is easily possible to determine and control the degree of the increasing stretch of the thread in the winding process in such a way that a very extensive compensation in the affinity to dyestuffs is achieved. According to the invention this is done, in that during the winding the interposed positively driven drawing-off roller or godet is made to run increasingly slower. This can be accomplished with various means, which per se are already known in the industry, for example by so-called conoid drives.

For the better understanding of the invention attention is drawn to the attached drawing representing three forms of execution of the invention and the following description.

Fig. 1 shows diagrammatically the spinning arrangement for the so-called spool-spinning-process;

Fig. 2 shows also the spinning arrangement for the spool-spinning-process in using an additional friction roller;

Fig. 3 shows the spinning arrangement for the centrifuge-process.

According to Fig. 1 the thread rises from the spinning nozzle *d* situated in the spinning bath on to the interposed, positively driven drawing-off roller *R* and from there it reaches via the transport roller *r* and through the traverse guide *F* the spinning bobbin *S*. The bobbin *S* is driven in a known manner in such a way that the draw-off speed of the thread remains approximately constant during the winding process. The positively driven and slip-free working drawing-off roller *R* is driven in such a way that it receives an increasingly slower draw-off speed in the course of the winding process.

According to the arrangement represented in Fig. 2 the operations are fundamentally the same as in Fig. 1. The drawing-off roller, which is interposed and driven positively and working at an increasingly diminishing draw-off speed, is marked *R*₁ in this case. Between this drawing-off roller or godet and the spinning bobbin *S* there is interposed another special roller *R*₂, over which the thread is conducted and which is driven at a constant speed, considerably greater

than the peripheral speed of the spinning bobbin, whereby the thread can slip over the roller R_2 .

In Fig. 3 it is a matter of producing centrifugal artificial silk and the positively driven winding member comprises the positively driven delivery godet R_2 , which per se is always present, and the spinning pot T . The prepositioned godet which is positively driven and works at an increasingly diminishing transport speed during the spinning process is here marked R_1 .

Having now described my invention what I claim is:

1. The process of producing artificial silk thread and the like of substantially uniform 15 denier and having improved dyeing properties which comprises extruding a cellulosic solution and passing the same through a setting bath, withdrawing the thus formed thread from the setting bath by passing the same around a godet 20 and thereby propelling the thread without gliding friction, passing the thread in its path of travel to a bobbin over another godet operating at a peripheral speed greater than the linear speed of the thread at that point so that a gliding contact occurs between the thread and the second 25 godet, collecting the thread at the bobbin at a greater linear speed than the peripheral speed of the first mentioned godet but at a lesser speed than the peripheral speed of the second mentioned godet, and gradually decreasing the speed 30 of the first mentioned godet during the winding of the thread, whereby objectionable characteristics resulting from contraction are avoided.

2. The process of producing artificial silk thread 35 and the like of substantially uniform denier and having improved dyeing properties which com-

prises extruding a cellulosic solution to form a thread, giving the thread different linear speeds at predetermined spaced points in its path of travel by passing the same after formation of the thread over a driven godet at the first of the spaced points in such a manner as to propel the thread without gliding friction, and then over a second driven godet at another of the spaced points having a peripheral speed greater than the first mentioned godet and allowing substantial 10 slippage of the thread with respect to the second godet, and gradually decreasing the speed of the first mentioned godet during the period of winding the thread on a bobbin while maintaining the speed of the second godet substantially constant 15 with the resultant increasing elongation of the thread while it is being wound on the bobbin whereby objectionable characteristics resulting from contraction are avoided.

3. The process of producing artificial silk 20 thread and the like of substantially uniform denier and having improved dyeing properties which comprises extruding a cellulosic solution into a spinning bath to form a thread, withdrawing the thread from the spinning bath by means 25 of a driven roller, passing the thread to a bobbin and collecting the same thereon at a substantially constant linear speed greater than the initial linear speed of the draw-off roller so as to stretch the thread, and during the spinning period 30 imparting an increasingly slower draw-off speed to the roller whereby succeeding portions of the thread are increasingly stretched as the thread is wound on the bobbin.
